UNITED STATES PATENT OFFICE.

FRED S. HOYT, OF DENVER, COLORADO, ASSIGNOR TO FULLER-STOW COMPANY, OF SAN FRANCISCO, CALIFORNIA, A CORPORATION OF CALIFORNIA.

APPARATUS FOR TREATING POROUS BLOCKS.

1,282,837.

Specification of Letters Patent. Patented Oct. 29, 1918.

Application filed February 1, 1916. Serial No. 75,603.

To all whom it may concern:

Be it known that I, FRED S. HOYT, a citizen of the United States, residing at the city and county of Denver and State of Colorado, have invented certain new and useful Improvements in Apparatus for Treating Porous Blocks; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to apparatus for treating porous blocks or bricks of any design whereby a filling material such as bitumen in the form of asphalt is forced into the pores of the material to be treated and allowed to solidify, thus rendering said material very durable and preventing it from absorbing moisture. My object is to provide an apparatus of this character which shall be exceedingly efficient in use and comparatively economical in construction.

As illustrated in the drawing, the apparatus generally speaking, comprises a retort adapted to receive the blocks or bricks which are preferably introduced by the employment of cars or wheeled supports upon which the blocks are mounted; a furnace for heating the said retort and its contents; a tank containing the bitumen or asphalt in liquid form and connected with the retort to permit the introduction of the liquid substance into the retort and also to permit the surplus liquid substance to be removed from the retort by air pressure and returned to the said tank by the same path through which it entered the retort from the tank; means for heating the tank for the purpose of liquefying the bitumen, asphalt or similar substance and maintaining it in the properly liquefied condition; and a pump which is employed for the double purpose of exhausting the air, moisture, etc., from the retort and from the pores of the blocks located in the retort, and also for the purpose of subjecting the contents of the retort to pressure for the purpose of saturating the porous blocks with the liquefied substance to the desired degree, and for the further purpose of removing the surplus asphalt or other liquefied substance from

the retort after the bricks or blocks have been so saturated. Other features of construction will be set forth in the detail description of this specification.

Having briefly outlined my improved construction as well as the function it is intended to subserve, I will proceed to describe the same in detail, reference being made to the accompanying drawing, in which is illustrated an embodiment thereof. In this drawing,—

Figure 1 is a vertical longitudinal section taken through the apparatus approximately on the line 1—1, Fig. 2, the parts, however, being shown on a smaller scale than in Fig. 2.

Fig. 2 is a vertical transverse section of the apparatus taken approximately on the line 2—2, Fig. 1, looking toward the right, but shown on a larger scale.

Fig. 3 is a vertical transverse section taken through the retort or treating chamber on the line 3—3, Fig. 4.

Fig. 4 is a vertical longitudinal section taken through the retort on the line 4—4, Fig. 3.

The same reference characters indicate the same parts in all the views.

Let the numeral 5 designate a retort adapted to receive the material to be treated, which, as shown in the drawing, is mounted upon cars or wheeled platforms 6 and run into the retort which is provided with track rails 7 for the purpose. This retort is equipped at its opposite extremities with heads 8 and 9 both of which may be removable or hinged to be opened if desired. As illustrated in the drawing, the head 9 is hinged as shown at 10 and secured in place when closed by means of bolts 12 which are hinged to the body of the retort as shown at 13 and engage slotted lugs 14 formed on the head, fastening nuts 15 being employed for securing the head in place. As it is necessary that the chamber of the retort be sealed or rendered as nearly air tight as possible, a packing ring or gasket 16 is employed, being located between the outer peripheral portion of the head and an opposing shoulder 17 formed on the adjacent extremity of the retort. This head 9 is preferably equipped with a perforated lug 18 to facilitate the opening of the head after the bolts 12 have been released. This opening act may be accomplished by the

employment of a cable 19 one extremity of which is connected with the lug 18 while the other extremity is accessible to the person in charge of the plant, the cable passing 5 over an elevated pulley 20, whereby the head may be quickly and easily raised to the horizontal position, as indicated by dotted lines in Fig. 1. After the head 9 is opened, track members or rails 21 are placed 10 in alinement with permanent rails 22 and extend from the latter into the retort as best indicated by dotted lines in Fig. 4. The cars or wheeled platforms 6 loaded with porous bricks or blocks 23 are then 15 run into the retort (see Fig. 4) after which the head 9 is closed and sealed.

This retort may be heated in any suitable manner. As shown in the drawing, a furnace 24 is employed and a burner 25 is illustrated 20 for supplying the heat. It is evident that any fuel in fluid form may be employed in connection with this burner, the passage of the fluid therethrough being controlled by a valve 26. The heat and products of combustion 25 enter the chamber 27 in which the retort is mounted through an opening 28 located at the rear extremity of the furnace 24. The chamber 27 is provided at its opposite sides with baffles 29 which engage the 30 retort on opposite sides about midway of its height, these baffles being interrupted at the opposite ends of the chamber 27 as shown at 30 and 31, the openings 31 being controlled by dampers 32 with which are connected 35 rods 33 having one extremity of each extending beyond the chamber 27 to permit the manipulation of the dampers from the outside. As shown in the drawing, fire tubes 34 extend longitudinally of the chamber 27 on opposite sides of and below the retort in order to allow the heat to circulate freely through the chamber 27 longitudinally, said chamber being provided with a number of transversely arranged partitions 35 which extend upwardly from the base of the chamber to the retort and terminate at the baffles 29, said partitions forming a support for the retort, the latter being preferably further supported from below 40 by a number of rollers or anti-frictional devices 36 to facilitate the necessary movement incident to the expansion and contraction of the metal of the retort due to varying temperature conditions.

55 After the bricks or porous blocks have been introduced into the retort and the latter sealed as heretofore explained, and after the temperature of the retort and its contents has been raised to the necessary degree, 60 say 300 degrees to 400 degrees Fahrenheit, the retort chamber is subjected to the necessary vacuum to exhaust the moisture, the air and other similar content from the pores or interstices of the bricks or blocks which 65 have been expanded by the action of the

heat. If desired, heated products of combustion from the chamber 27 may be introduced directly into the retort during the preliminary vacuum step for the purpose of supplementing the action of the vacuum condition 70 in removing the moisture. This may be done by opening a valve 37 located within the chamber 27 and in communication with the retort, the stem 38 of the valve being accessible from the outside. The valve 37 75 should, of course, be shut off after the bricks have become dried, in order that the necessary vacuum condition may afterward be produced. As illustrated in the drawing, I employ a pump 39 for exhausting the retort and removing the air, moisture and other similar content from the pores of the bricks or blocks, this pump being connected by means of a pipe 40 with the chamber of the retort. The pipe 40 is equipped with a 80 controlling valve 41 and is connected by means of a pipe 42 with a pressure gage 43 of any suitable construction.

After the chamber of the retort has been subjected to the necessary vacuum for removing as far as possible the original contents of the pores of the bricks or blocks, the valve 41 is closed and the liquid asphalt, bitumen or other similar or suitable liquefied substance is introduced into the chamber 90 of the retort in any suitable manner, a sufficient quantity being employed to completely submerge the porous bricks or blocks therein.

As shown in the drawing, the asphalt is 100 taken in liquid form from a tank 44 which is mounted in a chamber 45 which is in communication with the chamber 27 in which the retort is located, by way of an opening 46 whereby the products of combustion after 105 passing through the chamber 45 enter a stack 47. These products of combustion from the chamber 27 may be caused to pass forwardly or toward the left (see Fig. 1) 110 below side baffles 50 whereby they are caused to circulate practically the entire length of the chamber 45 both below and above the baffles; or they may be taken through the rear portion of the chamber 45 by opening a damper 51.

Originally or at the beginning of the operation, the bitumen, asphalt or other similar material to be liquified, is placed in the tank 44 through an opening in the top which is surrounded by a circular wall 48 which projects a short distance above the tank and is normally closed by a cover 49. Heat in addition to that received from the furnace 24 is obtained from a boiler furnace 52. Hot products of combustion from the furnace portion of the structure 52 are introduced into the chamber 45 through a conduit 53 and circulate around the tank 44, finally passing into the stack 47. Again, steam may be taken from the boiler portion of the struc- 115 120 125 130

ture 52 and delivered by way of the pipe 54 into coils or pipe members 56 located within the tank 44, the water of condensation being finally returned to the boiler by way 5 of a pipe 57. Furthermore, additional heat may be supplied to the chamber 45 from a burner 58 equipped with a valve 59. The temperature of the tank 44 should be high enough to place the asphalt in a thin liquid 10 condition. This temperature may, of course, vary as circumstances or the condition of the material under treatment may require. When in the properly heated and desired liquid or mobile condition the asphalt is 15 taken from the tank 44 through a pipe 60 and a branch pipe 61 controlled by a valve 62 and delivered to the retort 5. As shown in the drawing, the pipe 61 passes into the retort and its open extremity 62' is located near 20 the bottom of the retort but far enough above the same to permit freedom of discharge. The introduction of the liquid asphalt, bitumen or other proper material, into the retort, is continued until the porous bricks 25 or paving blocks are completely submerged therein, as heretofore stated. The valve 62 is then closed and pressure applied to the chamber of the retort from the pump 39 which may be employed as an air compressor 30 or for pumping air into the retort, as well as a vacuum pump for exhausting the air, moisture, etc., from the retort and from the pores of the bricks or blocks therein, as heretofore explained. It must be understood, however, that the pressure within the 35 retort chamber may be obtained in any suitable manner, but, as disclosed in the drawing, the pump 39 is employed for this purpose. The pressure within the retort by 40 the operation of this pump is such as to force as far as possible the liquid asphalt into the pores of the bricks, blocks or other material under treatment, its object being to force a greater amount of the liquid material into 45 the pores of the blocks than would naturally enter the same by the simple submersion of the blocks within the liquid asphalt. The pressure within the retort will be indicated by the gage and after it has reached the desired number of pounds per square inch 50 above atmospheric or the maximum pressure which it has been determined is necessary, the pump is stopped and if the pressure as indicated by the gage gradually diminishes, indicating that the pressure is relieved by the entrance of the liquid asphalt into the pores of the blocks, the pump is again started and the pressure again raised to the maximum, and this is repeated as 55 often as the gage indicates a reduction in pressure after the stopping of the pump, and as soon as the gage indicates that the maximum pressure is maintained after stopping the pump, the operator knows that the 60 blocks have been saturated or impregnated 65

to the maximum degree with the liquid asphalt. The valve 62 is then opened and the pump 39 started whereby air is forced into the retort under the necessary pressure to remove the surplus liquid asphalt from 70 the retort and returned to the tank 44 through the pipes 61 and 60 by way of which this material originally entered the retort; and after the surplus liquid asphalt has been completely removed, the retort may 75 be opened by first loosening the bolts 14 and lifting the head 9 to the dotted line position in Fig. 1, after which the auxiliary track rails 21 are put in place and the cars or wheeled platforms removed from the retort 80 whereby the bricks or porous blocks are allowed to cool in the atmosphere, whereby the asphalt contents of their pores become solidified, resulting in the production of an exceedingly durable article for paving and 85 other uses.

As soon as the treated porous blocks have been removed from the retort, the latter may be again charged in a similar manner, the head 9 sealed and the operation heretofore 90 described repeated.

In order that the temperature of the retort may be known at all times, the latter is equipped with forwardly and rearwardly located thermometers 63 and 64; and in 95 order that the depth of the liquid in the retort may be indicated, I place a float 65 therein and connect the same with a graduated tube 66 extending above the retort and exposed at all times for inspection. The 100 tank 44 is also equipped with thermometers 67 and 68.

If desired, instead of introducing asphalt, bitumen or other similar material in solid form into the tank 44, it may be introduced 105 in liquid form by utilizing an auxiliary pipe 69 equipped with a valve 70. This pipe 69 communicates with the pipe 60. In this event the valve 62 would, of course, be closed.

The retort, as illustrated in the drawing, is slightly tilted from its right-hand extremity downwardly, and if desired it may be drained by the employment of a pipe 71 having a normally closed valve 72.

From the foregoing description it is believed the operation of the mechanism will be readily understood. After heating the retort and its porous block contents through the medium of the furnace heretofore described and exhausting the chamber through the medium of the pump whereby the pores or interstices of the bricks, blocks or other material, have been freed as far as possible from air, moisture and other similar content, the liquid asphalt is introduced into the retort chamber while the latter is still under vacuum. The vacuum pump is, of course, stopped before the introduction of the asphalt, but, as the retort is sealed the vacu- 120 125 130

um condition remains. The introduction of the liquid asphalt to the retort is continued until the porous blocks are completely submerged. The valve 62 is then closed and the 5 retort placed under the necessary pressure through the medium of the pump to produce the maximum saturation or impregnation of the porous blocks with the liquefied substance. It should be understood that the 10 aforesaid high temperature of the retort is maintained during the entire process of producing the vacuum condition, the introduction of the liquid asphalt and the subjection of the contents of the retort to the 15 necessary pressure for the purpose. As soon as the desired or maximum saturation or impregnation of the porous blocks by the liquid asphalt has been attained, the valve 62 is opened, and by continuing the pressure 20 within the retort chamber the surplus asphalt is returned to the tank 44 through the same route which it entered the retort from the said tank, namely, through the pipes 60 and 62. As soon as this step in 25 the process is completed, the head 9 will be opened and the porous material immediately removed from the retort and allowed to cool, whereby the liquid contents of the pores of the blocks become solidified while 30 the latter are exposed to atmospheric pressure alone.

It has been found desirable in practice, after the removal of the surplus asphalt from the retort through the pipes 61 and 60, as 35 heretofore described, and returning the liquid material to the tank 44, to close the valve 62 and apply the maximum pressure through the medium of the pump 39 to the chamber of the retort, whereby the asphalt coating 40 of the bricks or blocks or a large part thereof may be forced into the pores of the said blocks whereby the latter are saturated to a somewhat higher degree, while at the same time the surplus coating upon the blocks is 45 virtually absorbed. This step of the process may be practised or not as may be desired.

Attention is called to the fact that the liquid asphalt, bitumen or other suitable 50 liquefied substance employed in treating the porous bricks or blocks, may be drained from the retort through a pipe 71 by opening a valve 72. This draining operation may be accomplished by gravity alone or 55 gravity may be supplemented or aided by pressure from the pump.

It should be explained that the gage 43 has 60 two members which are designated A and B respectively, one being utilized to indicate the air pressure within the retort and the other to indicate the vacuum condition in the retort. When either of these gage members is employed, the other is rendered inoperative or put out of commission by the 65 closing of a valve, the two valves being in-

dicated by the numerals C and D respectively.

Having thus described my invention, what I claim is,—

1. Apparatus for impregnating, comprising 70 a heating chamber, a retort in the chamber, a tank for impregnating material located within the heating chamber and above the retort, a conduit extending between the tank and retort, and means for creating a 75 pressure in the retort whereby the impregnating material therein may be forced back through the conduit into the tank.

2. Apparatus for impregnating, comprising 80 a heating chamber, a retort in the chamber, a tank for impregnating material located within the heating chamber and above the retort, a conduit extending between the tank and retort and provided with a valve 85 accessible from the exterior of the heating chamber, and means for creating a pressure in the retort whereby the impregnating material therein may be forced back through the conduit into the tank.

3. Apparatus for impregnating, comprising 90 a heating chamber, a retort therein, a tank for the impregnating material located in the chamber and above the retort, a conduit extending between the tank and retort at one end of the chamber and provided with 95 a valve accessible from the exterior of the chamber, and means outside the chamber and communicating with the opposite end of the retort for creating pressure therein.

4. In apparatus for treating porous blocks, 100 the combination of a retort in which the blocks may be submerged, a tank for supplying submerging liquid located at a higher level than the retort, a valve-controlled conduit for placing the tank in communication 105 with the retort and having its retort end open and located close to the bottom of the retort, and means in communication with the retort for placing the chamber of the latter under pressure whereby the liquid in 110 the retort may be returned to the supply tank through said conduit.

5. In apparatus for treating porous blocks, the combination of a retort adapted to receive the blocks, a tank for supplying liquid 115 to the retort in sufficient quantity to submerge the blocks, said tank being disposed at a higher level than the retort, a valve-controlled conduit for placing the tank in communication with the retort, the retort 120 end of the conduit entering the retort from above and being open and terminating but a short distance from the bottom of the retort, and means in communication with the retort for placing the chamber of the latter 125 under pressure greater than atmospheric.

6. In apparatus for treating porous blocks, the combination of a retort adapted to receive the blocks and adapted to hold liquid, a tank for supplying liquid to the retort in 130

- sufficient quantity to submerge said blocks, said tank being disposed at a higher level than the retort, a valve-controlled conduit for placing the tank in communication with the retort, the retort end of said conduit entering the retort from above and being open, extending into the retort and terminating near the bottom thereof, and means in communication with the retort both for exhausting the chamber of the retort and placing it under pressure greater than atmospheric. 7. In apparatus for treating porous blocks, the combination of a retort, a tank for supplying liquid to the retort and located at a higher level than the retort, means for heating the tank and its contents to maintain the latter in a liquefied condition, means for heating the retort and its contents, a valve-controlled conduit for placing the tank in communication with the retort, the retort extremity of said conduit being open, and extending into the retort from above and terminating near the bottom thereof, and a single instrumentality connected with the retort and serving both to produce a vacuum condition therein and also to place the same under pressure, as circumstances may require. 8. In apparatus for treating porous blocks, the combination of a retort adapted to receive said blocks, means for heating the retort exteriorly, means for introducing hot air or gas into the interior of the retort, means for exhausting the retort and for placing the same under pressure greater than atmospheric, a tank for supplying liquid to the retort located at a higher level than the retort, and a conduit connecting the tank with the retort, the retort extremity of said conduit being open, extending into the retort and terminating near the bottom thereof. 9. In an impregnating apparatus, the combination with a heating chamber, of means for heating the same, a retort disposed in said chamber at an angle to the horizontal, whereby one of its ends is positioned in a lower plane than the other, a tank for the impregnating agent also located in said chamber and arranged above said retort, a valve-controlled conduit extending downwardly from said tank into said retort and entering the lower end of the latter, the retort end of said conduit terminating at a point near the bottom of the retort, and means connected to said retort for creating pressure therein, whereby the impregnating material may be forced back to said tank through said conduit. In testimony whereof I affix my signature, in presence of two witnesses.
